UNITED STATES PATENT OFFICE.

GEORGE W. THOMAS, OF EAST LIVERPOOL, OHIO, ASSIGNOR TO R. THOMAS AND SONS COMPANY, OF EAST LIVERPOOL, OHIO, A CORPORATION OF OHIO.

DIE FOR SAGGARS AND THE LIKE.

No. 878,910.

Specification of Letters Patent.

Patented Feb. 11, 1908.

Application filed September 24, 1907. Serial No. 394,308.

To all whom it may concern:

Be it known that I, GEORGE W. THOMAS, a citizen of the United States of America, residing in the city of East Liverpool, in the 5 county of Columbiana, State of Ohio, have invented certain new and useful Improvements in Dies for Saggars and the Like, of which the following is a specification.

The object of my invention consists primarily in providing means whereby a saggars or the like may be readily removed without breaking from its die and comprises in details the features set forth hereinafter.

In the accompanying drawings in which 15 my invention is illustrated applied to a saggars die, Figure 1 is a side elevation partly broken away; Fig. 2 is a sectional plan of the same on the line 2—2, Fig. 1, and Fig. 3 is a vertical cross section thereof.

20 Referring to the drawings, the die proper 5 which is fastened to any suitable support through the basal flange 6, consists essentially of an outer shell 7 and an inner drum 8, between which the saggars (shown in dotted 25 lines in Fig. 3) is molded by the descent of the plunger 9. Considerable difficulty has been experienced in removing the saggars from the die without breakage and it is to this feature of the device that my invention 30 relates.

Very satisfactory results have been obtained I have found through using a vertically moving plate 10 carrying lifting rods one set of which 11 extend to a lifting ring 35 12 located normally at the bottom of the space between the drum and the outer shell and a second set 13 extending to the head 14 of the drum. I make this head separate from and of slightly less diameter than the 40 drum itself and support it upon the wall of the latter through a beveled shoulder, thus forming a scarfed joint so that the upper face of the head is flush with the outer edge of the wall as illustrated. It will be noted further 45 that the second set of rods 13 which extends to the head 14 are secured to the plate 10 with lost motion and when the die is in position for molding are really suspended from the head of the drum.

50 To remove a saggars from the die the lifting plate is raised by any suitable means. This actuates at once the rods 11 carrying the ring 12 and tends to lift the saggars up out of

the die. Immediately afterwards the lifting plate encounters the stops 16 on the rods 13 55 and lifts the head 14 thus supporting the bottom of the saggars, which is then lifted as a whole into the position shown in Fig. 3, whence it may be removed manually or otherwise, supported on the carrying ring 15. 60

The use of a lifting ring alone has been found inexpedient since the bottom of the saggars is very apt to adhere to the drum head, with the result that it is broken away from the sides as the latter are pushed up by 65 the ring. By making the drum head separate and also by delaying its rise until the lifting operation has already begun, the saggars bottom is not only supported during its rise but the air has a chance to enter between 70 it and the drum head and thus obviates the danger of breakage.

The arrangement shown and described is practical and serviceable but I do not limit myself to the particular features shown. 75

I claim as my invention:

1. In combination with a die for saggars and the like, a lifting mechanism for the saggars comprising a lifting ring and an independent drum head, and means for actuating both the ring and the drum head to lift the saggars from the die. 80

2. In combination with a die for saggars and the like, a lifting mechanism for the saggars comprising a lifting ring and an independent drum head of less diameter than the drum, and means for actuating both the ring and the drum head to lift the saggars from the die. 85

3. In combination with a die for saggars and the like, a lifting mechanism for the saggars comprising a lifting ring and an independent drum head, and means for actuating the same successively, the ring first, the head afterward, substantially as described. 90

4. In combination with a die for saggars and the like, a lifting mechanism for the saggars comprising a lifting ring and an independent drum head in combination with a lifting plate, rods rigidly attached thereto and extending to the lifting ring and a second set of rods attached thereto with lost motion and extending to said drum head, substantially as described. 100

5. In combination with a die for saggars

105

and the like having stationary outer shell and inner drum, a lifting mechanism for the saggar comprising a lifting ring interposed between said drum and shell, an independent drum head for the drum, a lifting lever and an operative connection therefrom to said ring and drum head.

In testimony whereof I have signed my name to this specification, in the presence of two subscribing witnesses.

GEORGE W. THOMAS.
